INVENTOR.

UNITED STATES PATENT OFFICE.

WALTER A. PAPWORTH, OF GRAND RAPIDS, MICHIGAN.

PORTABLE TYPEWRITING MACHINE.

Application filed May 27, 1921. Serial No. 472,967.

To all whom it may concern:

Be it known that I, WALTER A. PAPWORTH, a citizen of the United States, residing at Grand Rapids, in the county of Kent and

5 State of Michigan, have invented a new and useful Improvement in Portable Typewriting Machines, of which the following is a specification.

My invention relates to writing machines 10 of the portable kind, in which the parts are so arranged as to give the machine a form convenient for packing and carrying, and the weight is kept to the minimum consistent with strength. I am aware that type- 15 writers have heretofore been constructed of a form suitable for portability by folding the carriage and other parts of the machine, and also without folding any parts by using typebars of unusual shortness. The objects 20 of this invention are to provide a typewriter of very compact form, particularly as regards height, without folding any parts, and having typebars of the full length employed in the leading standard office machines, viz, 25 about three and one half inches. Further objects are to provide means for actuating the typebars which are very compact, simple, strong, and inexpensive, and which will impart an accelerating motion to the typebar 30 with minimum resistance to the fingers of the operator. Other objects will appear hereafter. These objects are attained by the mechanism illustrated in the accompanying 35 drawing which is a vertical section of the machine.

The frame F consists of a pair of side plates of substantially the outline illustrated, connected by transverse bars H and I at the front and rear, and by a front plate J. 40 Other transverse members A and Z, while not properly parts of the frame, are so proportioned and attached as to contribute greatly to the stiffness of the frame.

Across the rear upper part of the frame is 45 disposed a carriage support D, attached to the frame by parallel links, M and N, on each side of the machine, whereby the carriage support may be raised for printing capitals and figures. A carriage G is mounted to 50 travel on the carriage support, and carries a platen P around which the paper is wrapped to receive the type impressions.

The typebars B, bearing type T, are fulcrumed in a segment Z at the extreme lower 55 part of the machine, and when at rest extend diagonally forward and upward to the front

upper part of the machine. The typebar actuating means are contained entirely in the small triangular space beneath and in front of the typebars.

Extending across the machine and attached rigidly to the frame at each side is the action plate A which furnishes the principal diagonal stiffening to the machine and provides the support to which the several 60 parts of the typebar actuating means are attached and fulcrumed. This plate may be of one piece as illustrated, or may be built up of a number of members. At the rear it has a vertical portion containing slots 65 through which the rear ends of the key levers pass and slide. In front it has another upstanding portion containing vertical slots for the rock levers R. The lower edges of the slots furnish the fulcrums for the rock 70 levers. In the middle it has a series of hooks for the action springs S.

The rock levers R have a curved tongue-shaped part which passes through the slot in the action plate and contains a hole for at- 75 taching the front end of the action spring S. This tongue has a notch W in its lower side which fulcrums over the lower edge of the slot and permits the rock lever to rock, but will not permit it to move forward or back- 80 ward. The spring holds the rock lever snugly against its fulcrum and pulls its rear arm downward. The rear arm of the rock lever is provided with a hole at X, into which is hooked the front end of a link L connect- 85 ing the rock lever and typebar.

The key lever K is pivotally attached to the front end of the rock lever at V, and its rear end passes through and is free to slide in the slot in the rear of the action plate. 90 The key levers are guided by a comb C which extends across the machine.

In assembly the typebar segment and action plate are first fastened into the frame. The key lever and rock lever are fastened together with a fulcrum rivet at V before being placed in the machine. The rear end of the key lever is first inserted in its slot in the action plate, then as the key lever is swung upward, the tongue of the rock lever 100 is hooked into its slot in the action plate, and the spring S attached, holding these parts in their normal position. Then the link L and typebar B are put in, and these parts prevent the key lever and rock lever from going down far enough to permit the rock lever to unhook from the action plate.

As the key lever is depressed with the finger the key button is guided in a practically straight up-and-down motion by the front arm VW of the rock lever swinging about its fulcrum, while the rear end of the key lever slides backward and forward, thereby obviating the forward swing of the key button which would result if the key lever were hung on a fixed fulcrum.

10 The fulcrum points V, W, X, and Y, are so nearly in a straight line that when the key is first depressed the point X moves almost at right angles to the link, and the typebar is lifted very slowly at first. The 15 resistance due to the inertia of the typebar is thus very easily overcome, and although the several parts are rigid and inflexible, the action is light and pleasing.

Having thus described my invention, I 20 desire to claim as new:

1. In a typewriter, a frame, a platen mounted at the rear upper part of the frame, a segment mounted in the extreme lower part of the frame, an action plate extending 25 transversely across the frame in front of the segment; a key lever supported at its rear end so as to move backward and forward, a rock lever pivotally connected at its front end to the said key lever, extending rearwardly therefrom, and fulcrumed in the said 30 action plate; a typebar fulcrumed at the extreme lower part of the machine in the said segment, and a link operatively connecting the rear end of the rock lever with 35 the typebar; the whole co-operating together so that when the key lever is depressed it is constrained to move in a substantially vertical direction, the rear end of the rock lever is moved upwardly pulling on the link, and 40 the typebar is swung upwardly with increasing velocity until it strikes the platen.

2. In a typewriter, a platen mounted in the rear upper part of the machine, a segment mounted in the extreme lower part of 45 the machine, typebars fulcrumed in the said segment and extending upwardly and forwardly therefrom to the front upper part of the machine, links connected to the typebars and extending upwardly and forwardly 50 therefrom, a rock lever support having fulcrums for rock levers, rock levers fulcrumed in the said support having forwardly and rearwardly extending arms whose terminal centers are substantially in horizontal alignment with the said fulcrums, the rear ends 55 of said rock levers connecting with said links, key levers pivotally connected to front arms of said rock levers so as to swing downwardly therewith and extending backwardly 60 and downwardly beneath the rock levers and links to a support adapted to permit the rear ends of the key levers to move substantially horizontally backward and forward; the 65 whole co-operating so that when the finger keys are pressed downward they are con-

strained to move in a substantially vertical direction, the rear ends of the rock levers move upward and pull on the links, and an accelerating movement is imparted to the typebar, whereby the latter strikes the 70 platen.

3. In a typewriter, a frame, a key lever supported at its rear end in the extreme lower part of the frame so as to move backward and forward, a rock lever pivotally attached at its front end to the key lever and extending rearwardly in a substantially horizontal direction, a rock lever fulcrum mounted in the frame and supporting the rock lever, a spring attached to the rock lever and tending to keep it in normal position, a typebar segment mounted in the extreme lower part of the machine, a typebar fulcrumed in the segment, a link operatively connecting the rear end of the rock lever with the type bar, and a platen mounted in the rear upper part of the machine, the whole co-operating so that when the key lever is pressed downward in operation it is constrained to move in a substantially vertical direction, the rear end of the rock lever is actuated in a direction transverse to the length of the said link, and the typebar is caused to swing upward with an accelerating motion until it strikes the 85 platen.

4. In a typewriter, a key lever supported at its rear end so as to move backward and forward, a rock lever pivotally connected at its front end to the said key lever and having a tongue adapted to engage with a fulcrum plate, said tongue bearing a notch adapted to engage with a fulcrum, a rock lever support having at its front end an upstanding fulcrum plate provided with a slot to receive the tongue of the rock lever, the lower edge of the said slot being adapted to engage with the said notch and act as a fulcrum for the rock lever, and the said rock lever support having at its rear end a downwardly extending flange provided with a slot adapted to receive and support the rear end of the key lever, a spring attached to the said tongue on the rock lever and holding said tongue and notch firmly in engagement with the said fulcrum plate, the whole so proportioned and so co-operating that when the front end of the key lever is pressed downward it is constrained to move in a substantially vertical direction.

5. In a typewriter, a key lever supported at its rear end so as to move backward and forward, a rock lever pivotally connected to the key lever having a portion adapted to enter into interlocking pivotal engagement with a rock lever support when in abnormal position, a rock lever support having a portion adapted to receive and interlock with said rock lever, and adapted to receive and support the rear end of said key lever,

- and a spring attached to the said rock lever, holding it in engagement with said rock lever support, and holding the key lever in its uppermost position.
- 5 6. In a typewriter, a substantially horizontally positioned rock lever, a support on which the rock lever is pivotally mounted at a point between its front and rear ends, a key lever having pivotal connection near 70 its middle to the front end of the rock lever and at its rear end being pivotally and slidably mounted on the support, and a spring attached to the rock lever and said support acting to normally elevate the front end of the rock lever and attached key lever.
- 10 7. In a typewriter, a stationary support, a key lever having its rear end pivotally and slidably mounted thereon, a rock lever pivotally mounted between its ends and pivotally connected at its front end to the key lever at a point substantially midway between the ends of said key lever, said rock lever lying immediately to 75 the rear of the front end portion of the key lever and over the middle portion of said key lever, the whole cooperating so that the front end of the key lever moves up and down while the rear end slides backward and forward on its support.
- 15 8. In a typewriter, a support for key levers and rock levers connected to said key levers, comprising a single plate of sheet metal formed with a substantially upright front portion provided with slots in which the rock levers are adapted to be mounted, said plate being bent to the rear from the lower edge of said upright portion for a distance and then turned downwardly 80 to form a vertical rear portion, said downturned vertical rear portion of the plate having slots in which the rear ends of the key levers are received for pivotal and sliding movement.
- 20 9. In a typewriter, a substantially upright rock lever support plate having slots, rock levers having tongues passing through and pivotally engaging with said slots, and springs attached to the said tongues and adapted to prevent their disengagement 85 from the said slots.
- 25 10. In a typewriter, a supporting plate located at the lower front portion of the typewriter and including an intermediate substantially horizontal section, with a downturned rear end portion and an upturned front end portion, both of said end portions having vertical slots therein, rock levers pivotally mounted on the front upturned portion and having parts passing through said slots, and key levers pivotally connected between their ends to said rock levers and extending under said intermediate portion of the support and at their 90 rear ends passing through the slots in the downturned rear end portion of the plate.
- 30 11. In a typewriter, a sheet metal fulcrum plate provided with slots, rock levers disposed substantially at right angles to the fulcrum plate and having tongues shaped to enter into interlocking pivotal engagement with the said slots only when the rock levers are rotated to an abnormal degree, and key levers supported at their rear ends so as to move backward and forward, and pivotally connected to the front ends of the rock levers so that the front ends of the key levers are guided to move in a substantially vertical direction.
- 35 12. In a typewriter, a typebar pivotally mounted at its lower end at an extreme lower part of the machine a distance in front of the back of the machine and extending upwardly and forwardly to the front upper part of the machine, there being a substantially triangular space below the typebar, an operating rock lever, a support therefor, a spring attached to the support and the rock lever, and a key bar to which the rock lever is pivotally connected and which is mounted at its rear end on the support all located in said space, and a link connecting the rock lever with the key bar also located in 95 said space, substantially as and for the purposes described.
- 40 13. In a typewriter, means for actuating the typebars consisting of an action support, rock levers fulcrumed at the front of the action support, and key levers pivotally attached to the front ends of said rock levers and swinging downwardly therewith, the rear ends of the key levers being supported and guided by the rear part of said action plate and having a forward and backward sliding motion in relation thereto.
- 45 14. In a typewriter, a type bar pivotally mounted at its lower end at an extreme lower part of the machine and a distance in front of the back of the machine and extending upwardly and forwardly to the front upper part of the machine, there being a triangular space below the type bar, a key lever mounted at the front of the machine and extending at its rear end into 100 said space, and operative connections between the type bar and key lever for actuating the type bar on depression of the front end of the key lever, said key lever being mounted for movement of its rear end backward or forward on depression or elevation of the front end thereof.
- 50 15. In a typewriter, typebars fulcrumed at the extreme lower part of the machine and extending diagonally forward and upward to the front upper part of the machine, and forming thereby a triangular space beneath the typebars, the typebars forming one side of the triangle, the base of the typewriter another equal side, and the 105
- 55 16. In a typewriter, a typebar pivotally mounted at its lower end at an extreme lower part of the machine and extending forwardly to the front upper part of the machine, there being a triangular space below the typebar, a key lever mounted at the front of the machine and extending at its rear end into 110 said space, and operative connections between the typebar and key lever for actuating the typebar on depression of the front end of the key lever, said key lever being mounted for movement of its rear end backward or forward on depression or elevation of the front end thereof.
- 60 17. In a typewriter, a typebar pivotally mounted at its lower end at an extreme lower part of the machine and extending forwardly to the front upper part of the machine, there being a triangular space below the typebar, a key lever mounted at the front of the machine and extending at its rear end into 115 said space, and operative connections between the typebar and key lever for actuating the typebar on depression of the front end of the key lever, said key lever being mounted for movement of its rear end backward or forward on depression or elevation of the front end thereof.
- 65 18. In a typewriter, a typebar pivotally mounted at its lower end at an extreme lower part of the machine and extending forwardly to the front upper part of the machine, there being a triangular space below the typebar, a key lever mounted at the front of the machine and extending at its rear end into 120 said space, and operative connections between the typebar and key lever for actuating the typebar on depression of the front end of the key lever, said key lever being mounted for movement of its rear end backward or forward on depression or elevation of the front end thereof.
- 70 19. In a typewriter, a typebar pivotally mounted at its lower end at an extreme lower part of the machine and extending forwardly to the front upper part of the machine, there being a triangular space below the typebar, a key lever mounted at the front of the machine and extending at its rear end into 125 said space, and operative connections between the typebar and key lever for actuating the typebar on depression of the front end of the key lever, said key lever being mounted for movement of its rear end backward or forward on depression or elevation of the front end thereof.

connecting line the third; combined with key levers extending back into the said triangular space, and operative connections between the key levers and typebars situated within the above specified triangular space.

16. In a typewriter, a substantially horizontally positioned rock lever, a support on which the rock lever is pivotally mounted between its front and rear ends, a key lever, 10 a pivotal connection between the front end of the rock lever and the key lever at a point between the ends of the said key lever, said key lever being mounted for substantially vertical up and down movements of 15 its front end, a type bar pivotally mounted

back of the rock lever and at a point below the pivot of the rock lever, said type bar extending normally upward and toward the front at an angle to the horizontal and vertical, and a link connecting the rear end 20 of the rock lever with the type bar below the pivot of the type bar, substantially as described.

In testimony whereof I have affixed my signature in the presence of two witnesses, May 25, 1921.

WALTER A. PAPWORTH.
